United States Patent Office

Des. 206,674
Patented Jan. 10, 1967

206,674

CORN POPPER

John S. Hughes, East Rochester, and Douglas R. Cleminshaw, Syracuse, N.Y., assignors to Robeson Cutlery Co., Inc., Perry, N.Y., a corporation of New York

Filed Nov. 8, 1965, Ser. No. 88,035

Term of patent 14 years

(Cl. D44—1)

FIG. 1

FIG. 2

FIG. 3

FIG. 4

FIG. 1 is a front elevational view of a corn popper showing our new design;

FIG. 2 is an assembled view thereof, in elevation, taken from the right of FIG. 1;

FIG. 3 is a top view thereof; and

FIG. 4 is a bottom view thereof.

We claim:

The ornamental design for a corn popper, substantially as shown.
